(57) **CLAIM**

The ornamental design for a cover to cover a dripping container, as shown and described.

DESCRIPTION

FIG. 1 is a front view of a cover to cover a dripping container showing our new design;

FIG. 2 is a right side view thereof, the left side view is omitted because it is the same as the right side view;

FIG. 3 is a plan view thereof;

FIG. 4 is a bottom view thereof;

FIG. 5 is a perspective view thereof; and,

FIG. 6 is a cross-section view taken along the line 6-6 in FIG. 2.
